CLAIM

The ornamental design for a USB connector, as show and described.

DESCRIPTION

FIG. 1 is a left perspective view of a USB connector showing my new design;

FIG. 2 is a front elevational view thereof;

FIG. 3 is a rear elevational view thereof;

FIG. 4 is a left side elevational view thereof, the right side being a mirror image;

FIG. 5 is a top plan view thereof; and,

FIG. 6 is a bottom plan view thereof.

The broken lines are for illustrative purposes only and form no part of the claimed design.

The dash-dot-dot broken line and the even-broken line portions of the figure drawings are included to show unclaimed subject matter only and form no part of the claimed design.
